VIBRATING SCREEN

Emil Deister and Emil Edward Deister, Fort Wayne, Ind., assignors to Deister Machine Company, Fort Wayne, Ind.

Application May 14, 1931, Serial No. 537,287

1 Claim. (Cl. 209—382)

This invention pertains to vibrating screens and more particularly to means for imparting a sharp vibration to the screening medium, distinct from its vibratory movement.

5 In the present conventional vibrating screens considerable difficulty has been encountered in screening fine material, either wet or dry, and also coarser material, where the same is of a sticky or gummy nature. Numerous attempts 10 have been made to overcome the foregoing difficulties, and while these have met with some degree of success, they fail to completely solve the problem, and have also developed other serious objections.

15 In certain types of screens, the screening medium receives a hammer-like vibratory movement from an electro-magnetic actuated mechanism connected to the screening medium. This principle failed for several reasons, in that it is expensive, and the striker action is only effectively transmitted to the screen for an exceedingly limited distance.

Also, in devices of the foregoing character, it is necessary to subject the screening medium to 25 excessive tension in order to obtain any appreciable transmission of the tapping action, and this is objectionable in that strain upon the screening medium quickly fatigues and stretches the wires, materially reducing the useful life of 30 the screening medium.

Others have employed a cam mechanism for producing a hammer-like vibratory movement to the screening medium, but this also meets the foregoing objections.

35 Still another method comprises the attachment of a strip to the screening medium for engaging a rigid member carried by the frame. However, this has proven objectionable, as excessive amplitude of the vibratory movement would be necessary in order to obtain the required impact between the strip and the stationary member.

Furthermore, it will be appreciated that the vibratory strip must be held in control by the fine screen cloth, and therefore the wires soon 45 become fatigued and weakened, and because of the excessive vibratory movement required, soon crystallize.

Other objections reside in the fact that it is commercially impractical to maintain a sufficient 50 tension on the screening medium, so that the strip will uniformly engage the rigid member throughout its entire length. In other words, if the screen cloth is stretched too tight at one end, the tapping action is prevented at that point, whereas if left too loose, excessive whipping will

result. Furthermore, action of the strip can only be controlled or limited through the tension created upon the screen cloth, and when the same is properly adjusted, for light or no load, such adjustment will be incorrect for heavier material loads.

It is, therefore primarily the object of the present invention to overcome the foregoing objections by the provision of simple, inexpensive, and efficient means for imparting a sharp vibration to 10 the screening medium of a vibrating screen, distinct from its vibratory movement, and uniformly imparting a positive controlled tapping action to the entire screen surface without damage thereto.

15 Incidental to the foregoing, a more specific object resides in the provision of a plurality of hammers or strikers actuated solely through the vibratory movement of the screen, and adapted to engage vibratory means associated with a 20 screening medium, thus eliminating the necessity of excessive stretching and amplified vibratory movement, together with mutilation and wear of the screening medium, at the same time providing a sharp, positive tapping action over the entire 25 surface of the screening medium, independent of load or tension upon the screening medium.

A still further object resides in so mounting the hammers that in operation they serve to neutralize the action of each other, thus eliminating 30 twisting or strain on their support.

With the above and other objects in view, which will appear as the description proceeds, the invention resides in the novel construction, combination, and arrangement of parts substantially 35 as hereinafter described and more particularly defined by the appended claim, it being understood that such changes in the precise embodiment of the herein disclosed invention may be made as come within the scope of the claim.

40 In the accompanying drawings is illustrated one complete example of the physical embodiment of the present invention constructed according to the best mode so far devised for the practical application of the principles thereof.

45 In the drawings, Figure 1 is a longitudinal section through a conventional type of vibrating screen embodying one form of the present invention;

Figure 2 is a transverse section taken on the 50 line 2—2 of Figure 1;

Figure 3 is a detailed bottom plan view of one of the screen panels with the invention applied thereto; and

Figure 4 is an elevation of a screen panel illus- 55

trating a modified form of the invention attached thereto, parts being broken away and in section to more clearly illustrate the structural details.

5 Before taking up in detail the description and explanation of the accompanying drawings, it is to be understood that the present invention is applicable to any and all types of vibrating screens, regardless of structure or the manner in which 10 the screens are actuated, the present invention residing in the provision of means for imparting a sharp vibration to the screening medium per se, distinct from its vibratory action.

Furthermore, while the invention has been illustrated as applied to removable screen panels, such as are in common use at the present time, it is understood that the same is just as applicable to any screening medium, irrespective of the manner of attaching the same to the frame.

20 Merely for the purpose of illustrating one application of the invention, that general type of vibrating screen as disclosed in pending application filed February 24, 1931, Serial No. 517,730, has been shown. However, the invention is applicable to vibrating screens actuated by hammers, unbalanced shafts, eccentrics, or other mechanical means.

Considering the preferred form of the present invention, as illustrated in Figures 1 to 3 inclusive, the numeral 1 designates a base adapted to be supported upon any suitable foundation at approximately the angle desired. Mounted on the base are the spring seats 2 for reception of the coil springs 3, which in turn support the spring seats 4 secured to the side frames 5 of the vibrating screen section. Intermediate the ends of the side frames 5, the same are connected by the transverse irons 6, which carry the vibrating mechanism 7 of the overbalanced type, as disclosed in the aforesaid application, while the ends 40 of the side frames are connected by the transverse angle brace 6'.

Longitudinally secured to the inner faces of the side frame 5 are the supporting angles 8, which in the present instance receive a pair of screen panels 9, the latter being securely clamped on the supporting angles by means of the straps 10 engaging the sides of the panels and drawn into clamping engagement therewith by means of 50 the bolts 11 passing through the side frames 5.

For convenience of manufacture, the screening medium illustrated is formed in two sections or panels. However, as heretofore explained, the same may be constructed in one piece and secured 55 to the side frames in any suitable manner. Each panel 9 comprises a rigid channel frame 12 upon which a screen cloth 13 is secured by means of straps 14 bolted or otherwise secured to the channel frames 12.

60 In applying the present invention to the type of screen illustrated, one or more longitudinal vibrating strips 15 are provided, which may be secured to the angle irons 16 by welding or other suitable means, and in turn the angle irons 16 are bolted or secured to the channel frames 12 to bring the vibrating strips into engagement with the bottom surface of the screening medium 13, thus serving to normally support the same and eliminate strain thereon, as the result of loading, and avoiding the necessity of tautly fastening 65 the screening medium to the channel frame.

70 In the preferred form of the invention illustrated, the vibrating strips are shown as attached longitudinally to the screen panels 9. However, 75 it is to be understood that the same may be ap-

plied in various arrangements either transversely or longitudinally, and in any desired number, depending largely upon the size and shape of the screen.

5 In the preferred form illustrated, the transverse support 17 is secured to the channel frame of each panel by means of the brackets 18, or other suitable provision, and is preferably positioned centrally of the ends of each screen panel in order that the strikers hereinafter referred to may be 10 distributed with relation to the screening element to provide for uniform auxiliary vibration to the screening medium over its entire surface.

Suitably secured to the supports 17 are a plurality of strikers or hammers 19, each comprising 15 a resilient arm 20 having secured to its outer free end a weighted head 21, which upon actuation engages the vibrating strips 15. In order to prevent mutilation or wear of the vibrating strips by engagement of the strikers, the strips 20 have welded or secured to the bottom face thereof of striker plates 22, although it will be appreciated that these may be eliminated without affecting the principle of the invention. While in the drawings the weighted heads 21 of the strikers are 25 shown normally engaged with the striker plates 22, it is to be understood that a slight clearance may be provided, if desired, for effecting the hammer action of the strikers.

30 While it is not essential to the operation of the invention that the vibrating strips 15 be secured to the screening medium 13, it has been found that the same is preferable, in that a more positive vibration of the screening medium is obtained through the tapping action. Therefore, the vibrating strips 15 may be secured to the screening medium by means of retainer strips 23 bolted to the vibrating strips, or the retainer strips may be 35 eliminated, and the vibrating strip merely bolted to the screening medium.

40 Referring to the modification illustrated in Figure 4 of the drawings, it will be noted that the supports 17 have been eliminated, in which structure the hammers or strikers 19 are bolted or secured directly to the vibrating strips, and 45 while such structure will function to produce the desired results, particularly in small-sized screens, the preferred embodiment of the invention as heretofore described presents certain advantages, in that the striking action of the hammers is 50 entirely free, and in no way affected by any whip or yield in the vibrating strips 15, which might occur in the structure shown in Figure 4, particularly in a large-sized screen.

55 Taking up the operation of the invention, it is believed that the same will be quite apparent to those skilled in the art, in that as vibratory movement is imparted to the main frame of the screen through any suitable vibrating mechanism such as indicated at 7, the inertia of the weighted 60 strikers 19 will cause the same to produce a sharp positive hammer action against the vibrating strips 15, which in turn is transmitted to the screening medium 13 engaged by said strips, it being appreciated that the tapping action of 65 the hammers is entirely distinct from the vibratory movement of the screen. The foregoing sharp tapping action of the strikers effectively eliminates the tendency of fine or sticky material to blind or clog the screening medium, and in 70 view of the distributed position of the strikers, the sharp vibrations are transmitted substantially uniformly over the entire surface of the screening medium.

75 It will be noted in the preferred form of the 75

invention that the strikers 19 are secured to the support 17 in opposed relation, and therefore inasmuch as movement is simultaneously imparted to the opposed strikers they serve to neutralize 5 each other and avoid twisting strain on the supports.

The operation of the modified form of the invention illustrated in Figure 4 is for all practical purposes the same as that of the preferred 10 form, in that vibratory movement of the screen will impart action to the hammers 19, due to their inertia, causing the same to impart a tapping action upon the vibrating strips 15, which in turn is transmitted to the screening medium.

15 In all instances, it will be noted that the present invention is distinguished from other forms and types of auxiliary vibrating mechanisms, in that additional means is not required for actuating the 20 hammers or strikers, they being actuated as the result of the vibratory movement of the screen, resulting from the action of the primary vibrating mechanism.

From the foregoing explanation taken in connection with the accompanying drawings, it will 25 be readily seen that comparatively simple and highly efficient means has been provided for eliminating blinding of the screening medium in vibratory screens, by either extremely fine or sticky material, the screening medium being freed 30 from the material by the sharp, positive tapping action of the hammers, during the vibratory movement of the screen, and while a specific arrangement of vibrating strips and hammers has been illustrated and described, it is to be 35 understood that this may be varied in numerous ways, it being the purpose of the invention to so arrange the hammers and vibrating strips as

to obtain a substantially equal distribution of the tapping action over the entire surface of the screen.

In addition to the highly novel and efficient 5 operation of the present invention, particular attention is again directed to the advantages resulting from the structural features, in that the necessity of a taut or drum-tight screening medium is eliminated, and in addition thereto the vibrating strips serve to support the screening 10 medium for heavy loads, thus relieving strain thereon and materially increasing the useful life of the screening medium. Also, the tapping mechanism is such that the strikers or auxiliary 15 vibrating means does not act directly upon the screen, thus avoiding damage and mutilation of the same.

While the strikers or hammers 19 have been 20 illustrated and described as comprising weighted resilient arms, it is contemplated that other 25 structures may be employed, it being merely essential that the hammers have free controlled movement with relation to the vibratory movement of the screen.

We claim:

In a vibrating screen including a vertical vibrating frame and a screening medium carried thereby, a vibrating member carried by said frame and engaged with said screening medium, a support carried by said frame and positioned 30 below said screening medium, and a pair of opposed strikers carried by said support and vertically actuated by vibratory movement of said frame to produce a tapping action on said vibrating member. 35
